UNITED STATES PATENT OFFICE.

CLARE H. DRAPER, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

SHUTTLE-FEELER THREAD CUTTER.

Application filed December 18, 1925. Serial No. 76,203.

The present invention relates to an improvement in shuttle feeler thread cutters.

The Northrop Patent No. 1,515,515, dated November 11, 1924, illustrates and describes 5 a shuttle feeler thread cutter upon which the present invention is an improvement. It has been found with the construction of said patent that at times the thread to be cut misses presentation to the thread cutter, 10 and the object of the present invention is to provide the mechanism with a device for securing certainty of presentation of the filling to the thread cutter. To this end the invention consists in the improvement hereinafter described and particularly defined in 15 the claims.

In the accompanying drawings illustrating the preferred form of the invention, Fig. 1 is a side elevation of the hopper and associated parts of a weft replenishing loom, 20 showing the application of the thread parting and clamping mechanism thereto, the parts being shown in the position they occupy as the outgoing thread is about to be severed; and Fig. 2 is a plan of the end of 25 the lay, showing the relative position of the parts at this time.

In the illustrated embodiment of the invention the hopper 10, the transfer mechanism and all of the parts illustrated are the 30 same as in the mechanism illustrated and described in said patent. The thread cutting and clamping mechanism, indicated in a general way by the reference character C, is mounted on the shuttle feeler F, and operates as described in said patent. The breast beam 12 supports the mechanism in the usual manner. The lay 24 is of the form illustrated in said patent. In said patent the lay 40 was provided with a groove 30 to permit the movement of the shuttle feeler past the front upper corner of the lay beam without engagement therewith.

It has been found that with the mechanism 45 of said patent in operation it sometimes occurred that the outgoing thread T intended to be severed by the thread cutter, was too high and failed to enter between the blades of the thread cutter. In order to 50 prevent such operation, according to the present invention the loom is provided with a thread depressor 40 mounted on the breast beam, being, preferably, pivotally mounted at 41 upon a bracket 42, bolted on the rear

flange 43 of the breast beam 12. This thread 55 depressor is yieldingly held in the position illustrated in Fig. 1 by means of a spring 44. From the pivot 41 the depressor, which consists of a flat strip of metal, extends upwardly to a point near the upper front corner of the lay beam, from which point it extends rearwardly substantially parallel to the surface of the lay beam while the lay beam is in its foremost position, that is, while it is at front center, and thence it extends 60 with an upwardly inclined thread catching portion 45 beyond the reed. This thread depressor is located at the inner end of the shuttle box, and extends between the shuttle box and the reed as the lay beats up. The 65 inclined end of the thread depressor is adapted to engage the weft extending from the selvage to the spent bobbin, and during the last portion of the forward movement of the lay it engages the thread and depresses 70 it and presents it accurately to the thread cutter, (which moves between the end of the shuttle and the depressor), and thus it prevents the thread from passing over the upper knife of the cutter and securing greater 75 certainty of operation of the thread cutter. The thread depressor is normally stationary. In its preferred form its pivotal connection to its support permits it to be thrown forwardly. In the event that an improperly 80 boxed shuttle should strike it, the upwardly extended rear end of the depressor would be engaged by the shuttle, and swing the depressor upwardly out of the way so that it would not be broken or injured by striking 85 the shuttle. The device is simple in the extreme, and tends to secure certainty of operation 90 of the thread cutter.

Having thus described the invention, what is claimed is:

1. In a weft replenishing loom, the combination of the lay, a shuttle feeler provided with a thread severing device, and a thread depressor pivotally mounted independently 100 of the shuttle feeler on a stationary part of the loom in front of the lay and extending rearwardly to normally engage and depress the thread on each alternate beat-up movement of the lay that the normal action of the thread depressor may serve to position 105 the thread for the shuttle feeler severing device on the occurrence of replenishment of weft.

2. In a weft replenishing loom, the combination of the lay, a shuttle feeler provided with a thread severing device, a thread depressor yieldingly mounted on the breast beam of the loom for frontward movement independent of the shuttle feeler and extending rearwardly in normal position to engage the thread on each alternate beat-up movement of the lay, and said thread depressor having an upwardly inclined end portion which acts to depress the thread on alternate beats of the lay to insure its proper presentation to the shuttle feeler severing device on replenishment of weft. 35
3. In a weft replenishing loom, the combination of a shuttle feeler provided with a thread severing device, a thread depressor mounted on the loom frame in position to normally engage and depress the thread upon the surface of the lay between the warp and bobbin on each alternate beat-up movement of the lay, and yielding supporting means for the thread depressor for permitting the depressor to yield from its normally supported position when struck by an improperly boxed shuttle. 40
4. In a weft replenishing loom, the combination of a shuttle feeler provided with a thread severing device, a thread depressor having an upwardly inclined rear end and mounted on the loom frame in position to normally engage and depress the thread upon the surface of the lay between the warp and bobbin on each alternate beat-up move- 45
- ment of the lay, and yielding supporting means for the thread depressor for permitting the depressor to yield from its normally supported position when struck by an improperly boxed shuttle. 50
5. In a weft replenishing loom, the combination of the lay, a shuttle feeler provided with a thread severing device, and a thread depressor constituted as a strip of metal mounted on the loom frame in front of the lay and extending rearwardly in normal position to engage the thread above the lay on each alternate beat-up movement of the lay, the rear end of the depressor being inclined upwardly to pass above the thread rearwardly of the reed to insure depression of the thread onto the lay surface as the lay moves frontwardly. 55
6. In a weft replenishing loom, the combination of the lay, a shuttle feeler provided with a thread severing device, and a thread depressor constituted as a strip of metal pivotally mounted on the loom frame in front of the lay and extending rearwardly in normal position to engage the thread above the lay on each alternate beat-up movement of the lay, the rear end of the depressor being inclined upwardly to pass above the thread rearwardly of the reed to insure depression of the thread onto the lay surface as the lay moves frontwardly. 60

In testimony whereof I have signed my name to this specification.

CLARE H. DRAPER.
